TURNUBUCKLE

Matthew W. Le Doyen, Portsmouth, Va.

Application January 6, 1944, Serial No. 517,233

3 Claims.

(Cl. 287—60)

This invention relates to certain new and useful improvements in turnbuckles, and the primary object of the invention is to provide a turnbuckle embodying a pair of barrel sections that are separably connected in such a manner that they may be readily and quickly released for separation when desired.

A further object of the invention is to provide a turnbuckle of the above kind in which the barrel sections are co-operatively constructed in a novel manner to effect quickly releasable, separable connection thereof with each other.

Still another object of the invention is to provide a sectional turnbuckle of the above character which is comparatively simple, durable, and efficient in use.

The invention consists in the novel form, combination and arrangement of parts hereinafter more fully described, shown in the accompanying drawings and claimed.

In the drawings, wherein like reference characters indicate corresponding parts throughout the several views:

Figure 1 is a side elevational view of a turnbuckle constructed in accordance with the present invention.

Figure 2 is an edge elevational view looking toward the left of Figure 1.

Figure 3 is a top view thereof.

Figure 4 is a side elevational view of one of the barrel sections.

Figure 5 is a similar view of the other barrel section.

Figure 6 is a view of the section shown in Figure 4 as seen looking toward the left of the latter figure.

Figure 7 is an edge elevational view of the section shown in Figure 5 as seen looking toward the right of the latter figure, and

Figure 8 is a perspective view of the band for releasably retaining the barrel sections in connection relation.

Referring in detail to the drawings, the present turnbuckle includes a pair of oppositely disposed barrel sections 5 and 6, the section 5 including an internally threaded barrel 7 receiving a threaded rod 8 and provided with a pair of spaced longitudinally extending arms 9 and 10 on its inner end. The barrel section 6 includes an oppositely threaded barrel 11 receiving the oppositely threaded rod 12 and having a pair of spaced arms 13 and 14 projecting longitudinally from its inner end, the arms 13 and 14 being spaced apart a lesser distance than

the arms 9 and 10 for reception between the latter, as shown in Figure 1.

It will be noted that the arm 9 of section 5 is rigid and is formed on its inner face with a longitudinal series of teeth 15, while the arm 10 includes a short section 16 rigid with the barrel 7, and a terminal section 17 hinged at one end to the free end of the section 16, as at 18.

The arm 13 of barrel section 6 is formed in its outer face with a longitudinal series of recesses 19 which form a plurality of teeth 20 therebetween, and the teeth 15 and 20 are of similar size and form so that they will snugly interfit when the arms of the barrel section 6 are disposed between the arms of the barrel section 5, as shown in Figure 1. The arrangement is such that when the sections are interfitted, the free end of the arm 14 is located slightly beyond the pivot 18 of arm section 17, so that when a load is placed upon the turnbuckle there is a tendency for the sections to separate in a direction wherein the arm 13 moves away from the arm 9 and arm 14 causes outward swinging movement of the hinged arm section 17. However, means is provided for normally preventing this separation by holding the arm section 17 against outward swinging movement so as to retain the teeth 15 and 20 interengaged. This means preferably consists of a band 21 carried by the section 6 and slidable to a position wherein the same encircles the arms of both sections, and particularly the swinging arm section 17. To hold the band in this retaining position, said band is provided with a pair of transversely aligned openings 22, and the arm 14 has a transverse opening 23 adapted to align with the openings 22 for reception of a removable pin 24 which is preferably in the nature of an ordinary cotter pin adapted to be secured in place by spreading the terminals of its legs in a well known manner. The leg 14 also preferably has a second opening 25 near its free end in which is positioned a second pin 26 whose function is to simply prevent band 21 from sliding off of the barrel section 6 when the barrel sections are separated, thereby guarding against loss of the band 21.

With the parts positioned as shown in Figure 1, it will be seen that the barrel sections are effectively connected together so that the turnbuckle may be used in the ordinary way for adjusting the rods 8 and 12. However, when separation of the barrel sections is desired, it is simply necessary to remove the pin 24 and slide the band 21 off of the arm section 17. The load on

the turnbuckle will then act to tilt the section 6 relative to the section 5 so that arm 14 will cause outward swinging movement of arm section 17 for permitting the arms 9 and 13 to separate. When the latter takes place, the barrel sections quickly separate. To connect the barrel sections again, it is simply necessary to swing the arm section 17 outwardly and interengage the teeth of arms 9 and 13. Arm section 17 is then swung inwardly against the arm 14, whereupon band 21 is positioned to encircle the arms of both sections, and pin 24 is inserted to hold the band in retaining position.

From the foregoing description, it is believed that the construction and operation, as well as the advantages of the present invention, will be readily understood and appreciated by those skilled in the art. The invention provides for quick release of the barrel sections and embraces a construction which is comparatively simple but compact and durable.

What I claim as new is:

1. A turnbuckle comprising a pair of oppositely disposed barrel sections, each including a threaded barrel having a pair of spaced arms projecting longitudinally from the inner end thereof, the arms of one barrel section being spaced apart a lesser distance than those of the other barrel section so as to be received between the arms of said other barrel section, corresponding arms of said barrel sections being provided with interfitting teeth on the opposed faces thereof, one arm of said other barrel section including a hinged outer arm section mounted to swing toward or away from an arm of the first-named barrel section, and means to retain the hinged arm section in inwardly swung position so as to maintain the teeth of the barrel section arms interengaged.

2. A turnbuckle comprising a pair of oppositely disposed barrel sections, each including a threaded barrel having a pair of spaced arms projecting longitudinally from the inner end thereof, the arms of one barrel section being

spaced apart a lesser distance than those of the other barrel section so as to be received between the arms of said other barrel section, corresponding arms of said barrel sections being provided with interfitting teeth on the opposed faces thereof, one arm of said other barrel section including a hinged outer arm section mounted to swing toward or away from an arm of the first-named barrel section, and means to retain the hinged arm section in inwardly swung position so as to maintain the teeth of the barrel section arms interengaged, said last-named means comprising a band slideable onto and off of the arms of the barrel sections and positionable to encircle the arms of both barrel sections, and means to releasably retain the band in the last-named position.

3. A turnbuckle comprising a pair of oppositely disposed barrel sections, each including a threaded barrel having a pair of spaced arms projecting longitudinally from the inner end thereof, the arms of one barrel section being spaced apart a lesser distance than those of the other barrel section so as to be received between the arms of said other barrel section, corresponding arms of said barrel sections being provided with interfitting teeth on the opposed faces thereof, one arm of said other barrel section including a hinged outer arm section mounted to swing toward or away from an arm of the first-named barrel section, and means to retain the hinged arm section in inwardly swung position so as to maintain the teeth of the barrel section arms interengaged, said last-named means comprising a band slideable onto and off of the arms of the barrel sections and positionable to encircle the arms of both barrel sections, and means to releasably retain the band in the last-named position.

4. A turnbuckle comprising a pair of oppositely disposed barrel sections, each including a threaded barrel having a pair of spaced arms projecting longitudinally from the inner end thereof, the arms of one barrel section being

MATTHEW W. LE DOYEN.
